TWO PHASE ELECTROMAGNETIC DEVICE

Filed July 24, 1948

UNITED STATES PATENT OFFICE

2,654,393

TWO PHASE ELECTROMAGNETIC DEVICE

Edwin I. Ghormley, Dayton, Ohio, assignor to
 United Aircraft Products, Inc., Dayton, Ohio,
 a corporation of Ohio

Application July 24, 1948, Serial No. 40,559

3 Claims. (Cl. 137—657)

1

This invention relates to electromagnetically controlled devices and particularly to devices of that class wherein the core of the electromagnet has a relatively long travel, as in following the motion of a related part.

Electromagnetic devices of the kind to which this invention pertains comprise an energizable coil and a core or plunger movable in response to energizing of the coil to perform some function, such as operating a valve or a switch. The core is moved in an operating direction by attraction set up by the coil and is returned and held to its starting position by a spring. When the required motion of the core is slight, no structural problems arise and the size of the coil and the overall dimensions of the device may be relatively small. When a particular installation necessitates a longer travel of the core, however, certain problems arise which have heretofore been met only by increasing the size and strength of the coil. Among these problems is the fact that an increase in the core travel involves added return spring strength, and, moreover, multiplies the resistance or force rate of the spring. The coil must therefore be made large enough to overcome the initial and developed force of the spring. In installations wherein the spring further is used to return the valve, switch or other part actuated, a relatively heavy spring is required and correspondingly greater power must be built into the coil. Further a long core travel means that the magnetic attraction necessary to obtain initial motion of the core is applied across a long air gap. The force of attraction generated, therefore, must be increased in some proportion to the length of the gap.

It is an object of the present invention to meet the problems above noted in a manner other than by adding to the power of the solenoid mechanism. Related objects in this connection are, accordingly, to reduce the size and voltage of an electromagnet required to perform the following and other functions involving a long core travel; to make such an electromagnet more suitable for use in aircraft and like installations where smallness of size and lightness of weight are paramount considerations; and to present a generally new solenoid mechanism, simple and inexpensive of construction and characterized by reliable and efficient operation.

Another object of the invention is to introduce a new principle of operation in solenoid mechanisms wherein development and increase of the return spring force is eliminated over the major part of the working stroke of the core.

2

A further object is to obviate the need for applying magnetic attraction across a long gap in solenoids providing a long core travel. Still another object is to eliminate the return spring force in a solenoid mechanism while retaining a moving force in the direction of movement desired.

In carrying out the above objects there has been evolved an electro-magnetic mechanism characterized by a two part core unit, the operation of the mechanism taking place in a first phase wherein the core elements move relative to one another to overcome the return spring force and to initiate motion of the part controlled, and in a second phase wherein the core elements move as a unit to follow the motion of the part controlled without further opposition from the return spring.

Other objects and structural details of the invention will appear from the following description when read in connection with the accompanying drawing, which is a view in longitudinal section of a solenoid controlled valve embodying the present invention.

Referring to the drawing, the invention is disclosed as embodied in a solenoid controlled, pressure fluid operated valve for use in the hydraulic and fuel systems of aircraft and like installations.

The valve comprises a body 10 closed at its inner or right hand end and formed with a central bore 11. A series of radial ports 12 are formed in the body 10 adjacent the left hand or outer end thereof and communicate with bore 11. The ports 12 provide access to the bore 11 for fluid flowing under pressure in a passage (not shown) registering with the ports 12. The valve device, as shown, is designed to be inserted as a unit or package into a pump housing or the like, the body being externally threaded at 13 for connection with the housing.

Reciprocable within the bore 11 is a piston assembly 20 comprising a piston 14 connected by a stem of reduced diameter to a valve head 15 situated immediately outside the left hand end of the body 10. Valve 15 abuts against a ring 16 which surrounds the open end of bore 11 and provides a seat for the valve. The valve 15 is urged to a seat upon ring 16, in which position it closes off or prevents fluid flow out of the open end of bore 11, by a spring 17 contained in a housing 18 secured to the end of body 10. Housing 18 communicates with a passage (not shown) of low pressure relative to the passage supplying ports 12. Intermediate the piston 14 and valve

15 the piston assembly 20 is formed with a fluted guide or bearing member 19. Extending longitudinally through the piston assembly is a bore 21 constituting a fluid passage through the assembly. Within the inner or right hand end of piston 14 is a counterbore 22, into the bottom of which opens passage 21.

In the closed position of valve 15, the valve and piston 14 present approximately equal opposing areas to the pressure fluid admitted to bore 11 by way of ports 12. The piston assembly 20 accordingly normally is balanced and the spring 17 is effective to maintain the parts in the positions indicated. The piston 14 has a loose fit in the bore 11 in such manner that fluid within the bore may flow past the piston to the closed end of bore 11, which end thus becomes a pressure chamber designated at 23. Fluid within pressure chamber 23 normally may escape therefrom to the low pressure area through the longitudinal passage 21 so that no opportunity is afforded for the pressure in chamber 23 to rise sufficiently to overcome spring 17 and open valve 15. Should passage 21 be closed, however, the pressure in chamber 23 will rise and be effective to move the piston assembly in a direction to open valve 15. In that position of the parts the pressure fluid admitted to bore 11 through ports 12 is free to pass out of the bore around valve 15 to a place of discharge in the system. Then should passage 21 again be opened, the pressure in chamber 23 will be relieved and the fluid pressures acting upon the piston assembly will again come into balance whereupon the spring 17 may restore the parts to their starting position.

The passage 21 is controlled by a needle valve 24 reciprocable within counterbore 22 into and out of a seated position within passage 21. The needle valve 24 is formed on one end of a push rod 25 extending through pressure chamber 23 and out of the inner end of body 10 by way of a central opening 26 therein. Push rod 25 is surrounded for a part of its length by a cylindrical cage or housing 27 received in counterbore 22 of piston 14. The housing 27 has a slight clearance relatively to the side walls of counterbore 22 and abuts the bottom of the counterbore, the inner end of the housing having a central opening 28 through which the valve 24 projects toward passage 21. Radial slots (not shown) in the lower end of housing 27 place passage 21 in communication with counterbore 22. The push rod 25 has a collar 31 thereon near the valve 24. A compression spring 32 surrounds valve 24 and is interposed between the closed end of housing 27 and collar 31. The spring thus is effective to urge the push rod 25 and valve 24 thereon outward or in a direction normally to hold the valve in an open position relatively to passage 21.

The construction and arrangement is such as to permit a free flow of fluid from pressure chamber 23 to passage 21 while the valve 24 is open and to prevent such flow when the valve 24 is closed. Closure of valve 24 is brought about by an axial motion of push rod 25 in a left hand direction as viewed in the drawing against the resistance of spring 32. When the axial closing pressure applied to rod 25 is removed, the spring 32 is enabled to return the rod in the opposite direction whereby to move valve 24 out of its seat in passage 21 and reestablish communication between the passage and pressure chamber 23.

The push rod 25 extends through opening 26 in body 10 into cooperative relation with the solenoid mechanism. This mechanism comprises a

housing 33 one end of which is turned over upon a flange 34 on the body 10 and the other end of which has a lapped connection with a cap 35. The cap 35 provides a mounting for a connector 36 through which electrical leads 37 are introduced into the housing. The electrical leads 37 are operatively connected to a cylindrical, energizable coil 38 wound upon a spool assembly comprising a plate 39, a tube 41 and the end of body element 10. The tube 41 is received at its inner or left hand end in the opening 26 in body 10 and opens at that end into pressure chamber 23. At its opposite end the tube 41 projects through and beyond plate 39 and is closed at that end.

15 The tube 41 provides a bore for the reciprocation of a core movable therein in response to the electromagnetic attraction set up by coil 38. The core of the solenoid mechanism comprises a first or rearward plunger element 42 and a second or 20 forward plunger element 43. The plunger elements 42 and 43 are axially aligned and normally are separated by a slight gap 44. Forward plunger element 43 has a longitudinal opening 45 therein through which the push rod 25 is passed, 25 the outer or right hand end of the rod abutting element 42 and normally holding it in the outer end of tube 41 as indicated. The inner or left hand end of plunger element 43 is reduced in diameter and has a press fit with the aforementioned housing 27. Housing 27 thus is in effect rigidly connected to plunger element 43 which accordingly is limited and controlled in its movement by piston 14. This construction and arrangement of parts, in cooperation with the 30 spring pressure exerted by rod 25 upon plunger element 42 serves to define the gap 44 between the plunger elements. The plunger elements 42 and 43 are offset relatively to the horizontal center plane of the coil 38, and their mounting and the 35 size of coil 38 are such as to provide for a relatively long travel of the core within the coil.

40 When the coil 38 is energized the initial result is to effect a motion of plunger 42 relative to plunger element 43 to close the gap 44. In the course of such movement, push rod 25 is moved axially leftward and passage 21 in the piston assembly 20 is closed by valve 24. The fluid pressure in chamber 23 quickly rises in consequence of the closing of passage 21, and the piston assembly moves leftward to open valve 15. Coil 38 remains energized during this period, and, as the piston 14 moves leftward in bore 11, the plunger elements 42 and 43 also move leftward as a unit to maintain valve 24 in its seated position in passage 21. This motion is accomplished without additional resistance from the spring 32 since the spring and its cage or housing 27 move with the core elements 42 and 43. As long as the coil 38 continues energized, the parts will remain as above described and fluid flow occurs in the valve 45 through ports 12 and bore 11 past valve 15 to the low pressure area communicating with housing 18. When the solenoid coil 38 is de-energized, spring 32 is effective to move push rod 25 outwardly or in a right hand direction as viewed in the drawing and in so acting moves valve 24 out of its seat in passage 21 or to open position. With valve 24 open the pressure in chamber 23 is relieved through passage 21 and the piston assembly 50 is returned in a direction to close valve 15 by spring 17 as previously described. The return motion of piston 14 together with expansion of spring 32 effects a return of the plunger elements 42 and 43 to the starting positions shown in the drawing.

It will be understood that the invention has a scope unlimited by specific details of the illustrative embodiment thereof and that it is susceptible of uses and adaptations other than in the fluid pressure operated valve in connection with which it is here disclosed.

What is claimed is:

1. In an electromagnetic device, a housing, a cylindrical energizable coil in said housing, a two part metallic core reciprocable within said coil, said coil and said core being so arranged as to provide a relatively long travel of said core within said coil, said core being made up of axially aligned forward and rearward magnetic core elements, a forwardly extending tubular cage rigidly connected to the forward one of said core elements, a push rod having its one end within said cage and extending through said forward core element into contact with the rearward one of said core elements at its other end, a compression spring seated within the forward end of said cage and urging said push rod toward contact with the rearward one of said core elements, and movable means providing a positioning support for said cage and said forward core element, said movable means and said compression spring co-operating normally to define a relatively slight gap between said core elements, the energizing of said coil serving initially to close said gap and to overcome said spring, and serving subsequently to move said core elements as a unit under the control of said movable means.

2. An electromagnetically controlled valve device, comprising a body, a piston bore in said body, a piston in said bore, means for admitting pressure fluid to said bore to move said piston, a passage through said piston for the escape of pressure fluid from said bore, a valve reciprocable to open and close said passage, a spring urging said valve in a direction to open said passage, a housing for said spring limiting against said piston, a rod-like extension on said valve projecting axially through said spring housing, an energizable solenoid coil surrounding said extension, a two-part core reciprocable within said coil, said core comprising forward and rearward elements axially aligned and normally spaced from one another, said forward element being

rigidly connected to said spring housing, and an opening in the forward core element through which said rod-like extension passes into contact with the rearward core element, the energizing of said solenoid coil serving initially to close the space between said core elements whereby to move said valve against the urging of said spring to close said passage, subsequent motion of said piston being followed by said core elements as a unit to maintain said passage closed.

3. An electromagnetically controlled valve device, comprising a body, a piston bore in said body, a piston in said bore, a longitudinal fluid passage through said piston, a valve reciprocable in opposite directions to open and close said passage, a spring urging said valve in one of said directions, a housing for said spring limiting against said piston, a rod-like extension on said valve projecting axially through said spring housing, an energizable solenoid coil surrounding said extension, a two-part core reciprocable within said coil and comprising forward and rearward core elements axially aligned and normally spaced apart, said forward element being rigidly connected to said spring housing, and an opening in the forward core element through which said rod-like valve extension passes into contact with the rearward core element.
